FREDERICK DEACON MARSHALL, OF WEYBRIDGE, ENGLAND.

APPARATUS FOR PRODUCING COKE AND GAS FROM SOLID CARBONACEOUS MATERIAL.

Application filed April 10, 1926, Serial No. 101,072, and in Great Britain June 5, 1925. Renewed December 10, 1928.

This invention relates to apparatus for simultaneous manufacture of carbonaceous gas and coke. The main object of this invention is the production of carbonaceous gas from material which also produces coke, as the result of the distillation and carbonization of the material with which the apparatus is charged.

In the accompanying drawings illustrating the principle of this invention in the best mode now known to me of applying that principle,

Fig. 1 is a vertical, central section of the retort structure at line 1—1 of Fig. 3 showing a pair of top feed screws in elevation and illustrating by arrows the direction of fuel under carbonization and by other arrows the upward ascent of gas. The view also shows coke in the process of discharge from the under end of the retort.

Fig. 2 is a transverse section of the upper feeding casing structure at line 2—2 of Fig. 1 and shows the feed casing with a charge of carbonaceous material, such as bituminous coal, within the casing.

Fig. 3 is a transverse section through the retort casing proper and shows the relations of the cells for containing material to be carbonized, to the gas tubes or ducts.

Figs. 4 and 5 illustrate another form of the invention, Fig. 4 being a vertical central section of the retort structure at line 4—4 of Fig. 7 and Fig. 5 being a vertical central section at line 5—5 of Fig. 4.

Fig. 6 is a transverse section of the upper feed casing and with charge in place, at line 6—6 of Fig. 4; and

Fig. 7 is a transverse section of the retort at line 7—7 of Fig. 4.

Fig. 8 illustrates another form of cellular retort casing proper construction and wherein material to be carbonized is shown in place in vertical cells and wherein also gas ducts are shown.

Fig. 9 is a cross section at line 9—9 of Fig. 1 and shows the location of the gas outlets at the upper end portions of the gas tubes.

Fig. 10 is a vertical, central section of the shaft supporting gland structure with a feed screw shaft partially shown.

Fig. 11 is a cross-section of what is shown in Fig. 10 at line 11—11 of Fig. 10.

Figs. 12, 13, and 14 are views of a feed screw shaft reducing gear.

In the accompanying drawings, 1 is the retort casing proper wherein the material to be gasified and coked is contained. 2 is the head casing; 2^a are a pair of non-contacting feed screws which may either overlap or receive the peripheries of the helices just clearing each other; 3 are the gas ducts shown as connected by cross webs α to the inner sides of the retort casing. It will be noted that these ducts have gas escape openings at their upper end portions. Their tops are closed, but they are open at their under ends. The charge receiving cells 3^a are open both at top and bottom. The cell walls are indicated by 3^b. All the duct or passageway walls are connected by webs α . The retort casing 1 is enclosed by a spaced apart combustion or heating chamber wall 3^c.

To prevent coal or other material passing down the gas ducts, the open top of each is fitted with a cover or stopper S above the gas duct escape slots s.

4 is the expansion joint shown in this case at the bottom end of the retort casing and formed by an annulus which encloses the lower end of the retort casing 1 with a space between the exterior of the casing wall and the interior wall of the annulus. This space is filled with a suitable packing 4^a; 5 is the coke receptacle which forms the framework of balanced flap doors 6 shown attached to a rocker shaft 6^a, the ends of which are provided with counter weights 7 for closing and maintaining the doors in a closed position. 8 are the twin screw shafts; 9 is the gas outlet; 10 is the inlet for material under course of treatment; 11 are gas-tight supporting glands from which the screws depend.

12 is the turning gear which has been specially designed for the present purpose and which is connectible with an electric motor M by which a motor speed of 1000 revolutions per minute is reduced by means of the arrangement to give the feed screws a rotational speed of from 6 to 10 revolutions per hour.

The cross section for a retort 1 shown in Fig. 8 is merely another form of the cellular construction above described.

According to my present invention, the plurality of screws do not pass through the body of the retort casing or fill the same, but the screw propellers are situated in the separate head casing or upper section 2 which is at

tached to the upper end of the retort casing proper or lower section 1 which latter casing may be heated if desired by the described method of my copending application Ser. 5 No. 101,074 filed April 10, 1926, for the purpose of carbonizing, gasifying and coking the material passing through the retort. The casing 2 containing the screws is situated outside the zone of heat.

10 The short screws in the upper, non-heated casing 2 act as collectors of the material and propellers of the same to force the material which is fed by these screws or propellers downwards into through vertical ducts of the heated body of the retort casing or lower section 1, where the material undergoes carbonization or gasification. Said lower section 1 is the heatable, coal distillation structure of the apparatus.

20 The experience has been gained by the inventor to effect low temperature carbonization at a temperature ranging between 900°-1200° Fah. that the thickness of the material under the process of carbonization or gasification must not exceed four and one-half inches and that provision must be made for applying this heat to all four sides of the material.

30 As the density of the resultant coke from the material is entirely due not to temperature but to the expansion of the material while in a semi-carbonized or semi-plastic condition and as this expansion exerts a great force, provision must be made that the walls of the ducts through which the material is forced by the pressure, and also the screws are of sufficient strength to withstand the great pressure.

40 The bore of the upper, head casing 2 and of the lower carbonizing section is practically the same, and when both are seen empty they will represent a true bore from end to end of both sections when fitted together.

45 The bore of the upper section is filled by the two screws which can be of the overlapping but non-contacting type; or the screws need not overlap but just clear each other.

50 The bore of the lower casing or retort proper is, however, sub-divided in horizontal and vertical alignment by a number of radially or transversely disposed and lengthwise extending webs *a* and integral duct walls, but so that the ducts enclosed by the metal do not exceed approximately four and one-half inches in cross-sectional dimension. The rate 55 of the travel of heat through coal is about one inch per hour and practically and commercially considered, it is highly desirable that the cross-section of the ducts should not be over about four and one-half inches along the intermediate portions of the ducts, where the active distillation of the coal takes place, adjacent and above the lower portions of the ducts where the coking is progressively effected.

60 These radial and transverse webs are an in-

tegral part of the retort casing itself, being cast as part of the same; and by reason of the conductivity of cast iron and by molecular affinity of the iron, the heat applied to the exterior of the retort is conducted through all 70 the transverse and radially disposed members and is so imparted to the material which fills the retort cells or ducts during its passage through the same.

The said cells or ducts need not necessarily 75 be of the same cross-sectional area or shape as they may be so shaped as to produce slabs of coke, bearing always in mind the four and one-half inches condition or they may be disposed (Fig. 8) in honeycomb form for the 80 purpose of producing a briquette like form of coke.

The said members or walls forming the cells or ducts are located between the outer casing and inner hollow gas ducts for aiding the 85 rapid withdrawal of the evolved gases from the retort, and have nothing to do with the heating of the same.

During the evolution of the gases, the gas outlet is under the influence of minus atmospheric pressure owing to the action of the gas exhauster, not shown, but diagrammatically indicated.

90 The evolved gases find their way to their outlet through the centres of the charges of material as, owing to the pressure exerted on all sides by the expansion of the charges during carbonization, very little or no gas can 95 find its way up between the outer sides of the charges and the inner surfaces of the containing 100 cells or ducts.

105 The coal and gas ducts being open at each end are naturally susceptible to the exhauster suction on the interior of the retort generally, and as the evolved gases seek to leave the centres of the charges by the path offering the least resistance, it is open for these 110 gases to leave partly direct through the upper portion of the charges or partly through the lower ends of the gas ducts, and the arrows in the drawing show the approximate paths the gases take. The coal or distillation ducts are open at their upper and under ends. The gas ducts are open at their under ends, and though closed at their upper 115 end openings by members *S* in order to prevent the coal from being forced down into them and so clogging the ducts, are provided at their upper end portions adjacent the members *S* with gas escape ports *s*.

120 Much value is attached to these ducts as the easier and with less resistance the gases can escape, the chances of their being "cracked" or split up is greatly lessened.

125 To increase the throughput capacity of the retort, the divisions or webs in the retort may be disposed in an annular manner and, provided all divisions are connected physically with the inner wall of the retort, the carbonization of the interior columns of ma-

terial, coal or coke, will be as equally well effected as in the outer columns of material, coal or coke.

The power exerted by the co-acting feed screws in the upper casing on the mass of material forced through the lower casing is enormous and provision has to be made to eject the charge of carbonized coke from the casing automatically and continuously before the pressure on the material leads to destructive consequences.

According to the present form of my invention, this is effected by the installation, at the lower end of the lower casing or section 1 of a coke box or receptacle within which a pair of flap doors 6 are installed working on hinges; and which, when in a horizontal condition, close the bottom of the superimposed casing in a practically gas tight manner as the edges of the flaps are bevelled to the same angle as the tapering sides of the coke box or receptacle against which they contact, so that the foot of the columns of coke in the casing rest on the flaps which are kept in position by a lever attached to each flap which levers are controlled by weights or springs.

The desired pressure to be exerted by the co-acting screws on the charge of material, to force the same through the lower casing, having been ascertained, the levers are weighted accordingly so that when the pressure on the charge reaches a certain point the flaps are forced open and a portion of the charge in the form of coke is ejected into the gas-tight box or receptacle below the flaps. When the pressure is relieved, the weight on the levers causes the flaps to return to a horizontal position.

At intervals the coke receptacle is opened and the coke removed during which period the revolution of the co-acting screws may be stopped and the flaps held up to ensure against the entering of air into the retort casing.

The design of the flap doors 6 may be varied and instead of hinging them on their long sides they may be hinged on their short sides in either case being controlled by the outside levers fitted with either weights or springs. The flap doors 6 are merely one form of coke escape control apparatus for also offering a resistance to the downward feeding pressure and load of the coal in its initial condition, in its active distillation and gas evolving condition, and in its progressive coking in the lower portion of each distillation duct.

The density of the coke can be varied by the amount of pressure it is subjected to during its formation in the retort and this controllable variation of pressure is another feature of my invention.

To take up the expansion of the retort in a vertically, longitudinal direction, it is pro-

posed to intervene either between the upper non-heated casing or the lower non-heated section represented by the coke receptacle a loose joint of any desired construction.

Each gland 11 comprises an upstanding, 70 annular, capped casing to which the reference 11 is applied. The casing has a bottom that is solid except for a central shaft opening through which a shaft 8 extends upwardly through the fixed cover plate 13 of casing 2, 75 and upwardly through the fixed cover 14 of casing 11 for reception of members of the turning gear 12. Within the gland casing, there is at its bottom portion a pair of disc-shaped ball races 15 between which anti-friction 80 balls 16 are located, the shaft passing through the races and upwardly through a piston 17 provided with piston rings 18. The piston is pinned to the shaft by pins 19 and has a length less than the distance between 85 the upper race 18 and the gland casing cover, leaving a clear space 20 into which the piston may ascend on elongation of the shaft due to heat. Each screw is suspended from its piston which normally rests on the upper race, 90 The bottom of the gland casing is provided with a packing *p* around the screw shaft and the gland as a whole is gas-tight and constitutes a gas-tight, anti-friction screw suspending mechanism that permits endwise 95 movement of the suspended screw.

The turning gear or driving mechanism which is fixed on the upper casing cover, although it may be otherwise supported, includes an addition to the gear 12 which is a 100 spur gear, one on the upper end of each screw shaft, an intermediate spur gear 21 in mesh with gears 12. Worm gear 22 is mounted on the upper end portion of a vertical stub shaft 23 and effects rotation of the screw shafts 105 simultaneously in the same direction. Worm gear 22 is in mesh with a worm 25 on a horizontal shaft 26 which is provided with a worm gear 27. This worm gear 27 is in mesh with an intermediate worm 28 on a shaft 24 also 110 carrying a worm wheel 24^a in mesh with a worm 29 on the shaft 30 of a motor M. This driving gear serves to reduce a motor speed of about 1000 revolutions per minute to a screw rotational speed of from six to ten 115 revolutions per hour, as above stated.

The stoppers S at the upper ends of the gas tubes are fixed in place, thus preventing entrance of the material into the gas tubes or passageways; but the gas exits ports *s* are continuously open so that the generated gas may continuously escape therethrough, into the communicating space S' and then to the exit 9, while the retorting operation is active.

The rocker shaft 6^a mounted in openings of 125 the wall of the receiver 5 for coke or other residue of distillation, extends at both ends outwardly of the receiver. Each end has a dependent arm 6^b for reception of one or more removable weights 7, two of which are shown 130

on each arm. The weights may be increased or diminished in number according to the character of the material to be treated. Receiver 5 is practically air-tight and is provided with an opening 5^a through which the residue of distillation may be removed from time to time. Each opening is shown provided with a door 5^b.

The combustion chamber 3^a is for heat applied during the retorting operation which may be a low temperature operation for which the apparatus is especially intended.

The intake 10 is provided, in practice, with a gas-tight charging device 10^a of any desired construction, the charging device is herein indicated diagrammatically.

In operation, succeeding initial charging, charge arresting and carbonization, the feed screws may be driven continuously and the charge arresting doors may be continuously opened for either partial momentary interruption in escape, or, for continuous escape, of the coke into the coke box, with the box door closed to prevent inrush of air, all depending on the character of the material treated and the desire of the operator.

The described arrangement for disposition of the descending material in a plurality of relatively small, cross-sectional and relatively thin walled, lengthwise extending tubes and for simultaneous ascent of evolved gas through the corresponding gas tubes, insures a perfection of carbonization or distillation attended by maximum evolution by gas from the material.

Evolution and removal of the gas is continuous. The charging operation may be continuous or intermittent depending on the type of charging apparatus used. The discharge of the coke into the coke box is automatically intermittent.

In Fig. 5, the gas escape 9 is shown discharging into a diagrammatically illustrated exhauster 9^a. The exhauster connection is sufficient in practice to effect the ascent of gas into the escape 9, notwithstanding the pressure on the charge between the feed screws and flap doors. Some of the ascending gas escapes from fissures in the coke and some of it from material M thereabove.

The coal ducts referred to may be properly designated as distillation ducts. The under helices of the feed screws are effective to force and break up said material against the upper ends of the distillation duct walls and for forcing the material downwardly into and through the ducts. When the coal ducts are filled and the feed screws are in action, the coal or other material is forced into the upper, open ends of the coal ducts and is under constant pressure downwardly to the coke discharge control apparatus. While this apparatus permits, by vibration of the free edges of the flap doors on which the coke initially rests, continuous escape

of the coke according to adjustments of the weights 7, the apparatus, nevertheless, offers such a resistance to the downward pressure that the pressure densifies the coke substantially and firm coke is produced. It will be observed that the heatable, metal walls of the coal and gas ducts are integral and serve to conduct exteriorly applied heat to and through the material in the coal ducts; and that there is a plurality of coal ducts subjacent the under end of each feed screw. The integrally and metallically walled, coal ducts are raised to a temperature sufficient to render portions of the coal, as it is forced compressively downward from the upper end portion of the coal ducts, plastic; and in this condition gas is freely evolved, the plastic condition permitting the feed screw pressures to condense and solidify the coke formed in the lower portion of the coal ducts against the flap doors or gates carried by the adjustable, weighted rocker shafts 6. When the apparatus is in operation these flap doors or gates are never closed, but are constantly vibrating and thus permit continuous discharge of the solidified or densified coke which, with all the superincumbent material in the coal ducts, is under continuous downward pressure by the feed screws. The feed screws and their operating mechanism constitute, in effect, a continuously operable means for feeding and also forcing the coal or other gasifiable and coke producing material into and through the distillation ducts and compressing the coke into an extremely firm, dense coke against the resistance offered by the coke control discharge means operable to form a resistance to the compressive densification of the coking, plastic material thereabove. The feed screws are spiral screws of the same hand and are shown of the same pitch. The cross section of each screw is that of a spiral screw. The screw helix of each screw extends from an intermediate portion of its shaft downwardly to the end of the shaft and the upper casing section in which the feed screws are mounted is provided with the preliminary or initial charging or coal feeding device 10^a as well as with the gas escape conduit 9 leading into a suitable exhauster 9^a.

The coal becomes plastic in a stratum or in strata where it changes into coke. By keeping the in-fed coal and the coking plastic stratum or strata under constant pressure as described, the formation of thin and fragile walled coke cells is prevented and a dense compact coke product obtained. Such a densification is of very great importance to the coke product as it does not break up or give off coke dust as is the case with coarsely cellular coke. Moreover, the constant compression is favorable to evolution of the gas evolving from the coking portion of the coal and from the coal.

What I claim is:

1. In apparatus for simultaneous production of gas and coke from carbonaceous material, the combination of an upright casing having an upper and a lower section; said upper section being provided with a preliminary coal charging apparatus, and means to effect escape of ascending gas or gaseous vapor, and being open at its under end for discharge of the material under feed screw pressure; and, a plurality of adjacent vertical, downwardly feeding, spiral feed screws of the same hand within said upper section of the casing; said lower section of the casing being of metal and being provided with a plurality of vertical, metal distillation duct walls having their upper ends opposed to and spaced apart from the under end of each of said feed screws, each feed screw having a cross section dimensioned to cover a plurality of the upper ends of the ducts, and the distillation ducts being open at their lower ends above the bottom wall of the lower section of the casing, for escape of gas and coke; mechanism for removing the coke; mechanism for rotating said feed screws; a combustion chamber around the distillation duct walls; each of said feed screws being effective to force said material into the upper ends thereof and for forcing the material downwardly into and through the ducts; the duct walls conducting heat received by them to the carbonaceous material in the ducts; and gas off-take ducts extending upwardly from the lower portion of the under section.
2. In apparatus of the class described, the combination of a plurality of upright, continuously revoluble, spiral feed screws of the same hand mounted within a casing and arranged to deliver and to force material continuously downwardly into the upper open ends of a series of integrally and metal walled elongated, upright ducts of small cross section relatively to that of the casing above the ducts, and through and out of said ducts; each feed screw being dimensioned to cover a plurality of the upper ends of the ducts; and upright metal structure provided with said ducts, means for exteriorly heating said metal structure to render plastic therein descending portions of the material for evolution of gas and production of coke in lower portions of said ducts; and continuously operable, coke discharge control mechanism effective to offer resistance to the pressure produced by the downward feed of the material; and means for conducting the generated gas upwardly and out of the apparatus; said feed screws having their under ends adjacent, but spaced apart from, the upper open ends of said ducts; and said integrally and metal walled ducts being arranged in parallel groups wherein each group comprises a plurality of ducts subjacent the under end of each feed screw.
3. In coal gas and compressed coke making apparatus, the combination of a continuously operable, coal feeding mechanism, said mechanism including a casing and spiral feed screws mounted therein; a coke discharge control mechanism; and, interposed between said feed screws and said coke discharge control mechanism, an elongated, metal distillation structure having a plurality of sets of open-ended, lengthwise extending, distillation ducts grouped in each set around and enclosing a gas escape duct, the ducts in each set of distillation ducts being opposed to one of said feed screws, each feed screw being dimensioned to cover the upper ends of a plurality of said ducts; the walls of all the ducts being integral, and each feeding mechanism being operable not only to feed into adjacent open ends of said distillation ducts, but also to force the material fed compressively into and to fill the same, to compress therein formed coke against the resistance of the coke discharge control mechanism when the same is in coke arresting position, and past the same when it is in position for discharge of coke; said coke escape control mechanism being operable to arrest and resist the escape of coke against the pressure of said coal feeding mechanisms and also permit the discharge of the coke; and means for exteriorly heating said structure; the ends of the gas escape ducts adjacent the coal feeding mechanisms being closed to prevent in-feed of coal and adjacently provided with gas escape ports; and the ends of said gas escape ducts adjacent the coke discharge control mechanism being open for intake of gas.

Signed at New York city, in the county of New York and State of New York, this 12th day of March A. D. 1926.

FREDERICK DEACON MARSHALL.
